UNITED STATES PATENT OFFICE.

JAMES W. BEATTIE, OF RUTLAND, VERMONT.

DESIGN FOR FLY-PAPER.

SPECIFICATION forming part of Design No. 25,960, dated August 18, 1896.

Application filed July 8, 1896. Serial No. 598,483. Term of patent 14 years.

To all whom it may concern:

Be it known that I, JAMES W. BEATTIE, a citizen of the United States, residing at Rutland, in the county of Rutland and State of Vermont, have invented and produced a certain new and original Design for Sheets of Sticky Fly-Paper; and I do hereby declare the following to be a full, clear, and exact description thereof, reference being had to the accompanying drawing, forming a part of this specification.

The figure is a top or plan view of a sheet of sticky fly-paper showing my design, this view being deemed sufficient to fully illustrate the invention.

The leading feature of my design consists in the body of a sheet of sticky fly-paper of a very dark color, as black, dark blue, dark brown, or other deep-hued color, with a cir-

cular figure thereupon, said figure being filled in with a color lighter than the background or body of the sheet, this lighter-colored figure to represent a dish or saucer placed upon a tray or dark mat for the purpose of attracting flies thereto, and by reason of the dark color of the background the flies that are entangled in the sticky surface of the sheet will not be so readily seen and avoided by the flies passing near-by.

What I claim is—

The design for a sheet of sticky fly-paper, substantially as shown and described.

In testimony whereof I affix my signature in presence of two witnesses.

JAMES W. BEATTIE.

Witnesses:

F. P. BILLINGS,
C. M. JASEMIE.
